Primary Examiner — Steven J Czyz*Assistant Examiner* — Varun Salil Kamat(74) *Attorney, Agent, or Firm* — Jose Cherson Weissbrot(57) **CLAIM**

The ornamental design for a soap dispenser as shown and described.

DESCRIPTION

FIG. 1 is a front perspective view of a soap dispenser, showing my new design;

FIG. 2 is a rear perspective view thereof;

FIG. 3 is a front elevational view thereof;

FIG. 4 is a rear elevational view thereof;

FIG. 5 is a left elevational view thereof;

FIG. 6 is a right side view thereof;

FIG. 7 is a top side view thereof; and,

FIG. 8 is a bottom plan view thereof.

The broken lines in the figures are for the purposes of illustrating portions of the soap dispenser, which form no part of the claimed design.

1 Claim, 8 Drawing Sheets(56)
